CLAIM

The ornamental design for combination beach towel and beach cover-up, as shown and described.

DESCRIPTION

FIG. 1 is a perspective view of a combination beach towel and beach cover-up showing my new design, shown partially broken away;

FIG. 2 is a front elevational view thereof;

FIG. 3 is a rear elevational view thereof; and

FIG. 4 is a left side elevational view thereof.

The human figure shown in FIGS. 2-4 is in broken lines for illustrative purposes only.
